LIQUID FUEL BURNING APPARATUS

Theodore B. Focke, Cleveland Heights, Ohio, assignor to Perfection Stove Company, Cleveland, Ohio, a corporation of Ohio

Application May 16, 1939, Serial No. 273,969

7 Claims. (Cl. 236—68)

This invention relates to fuel feeding and governing means for liquid fuel burners of the kind suitable for use in the heating plants of houses or other buildings, and whose operating range includes low or pilot fire, intermediate fire, and high fire, fuel being fed at no time during operation in an amount less than that required to maintain operation at low or pilot fire.

An object of the invention is to provide, in fuel feeding and governing means, a multiple valve that operates in a single chamber, the same consisting in its present preferred form of an outer sleeve valve and an inner valve element or tube operating within the sleeve, the sleeve having a working fit in a chamber through the side of which a port opens, a second port opening into the chamber in opposed relation to the end of the inner valve element.

Another object, attained through the use of a tubular inner valve element that extends well above the maximum liquid level and in open communication with the atmosphere, is to effectively vent the fuel feeding means.

A further object is to provide an automatic control system for said multiple valve, desirably thermostatic in character and involving a thermostatic switch or so-called room thermostat exposed to the temperature of the space or apartment heated by the burner, together with electrically energized means for operating the valve elements, and the necessary electrical circuits involving the foregoing, so organized that under what may be termed normal conditions, when the space or room temperature is within a given limited range, and with the valve actuating circuits open, sufficient fuel will be fed, in addition to that for maintaining low or pilot fire, to sustain operation of the burner at intermediate fire. When the room temperature exceeds said given range the control system functions to shut off the supply of additional fuel, and when the room temperature is below said range the system operates to increase the additional fuel supply to that required for high fire. It is evident from the foregoing that in case of failure of the electrical circuit, the burner will continue to operate at intermediate fire, which provides a safe temperature under all circumstances, until the difficulty is rectified or until the apparatus is manually adjusted to meet prevailing conditions.

These objects, with others hereinafter appearing, are attained in the embodiment of the invention illustrated in the accompanying drawings wherein Fig. 1 is a diagrammatic representation of my improved fuel feeding and governing means

associated with a liquid fuel burning apparatus wherein the burner is of the bowl or pot type; Fig. 2 is a plan view of the unit of the fuel feeding and governing means that includes the multiple valve feature of my invention, with the float chamber and other associated parts, the construction being substantially that employed in practice, and the view showing the cover of the float chamber removed; Fig. 3 is a plan view of the cover of the float chamber and the valve actuating means mounted thereon; Fig. 4 is a vertical section through the aforesaid unit on the line 4—4 of Fig. 2; Fig. 5 is a sectional detail on the line 5—5 of Fig. 4 showing the multiple valve and adjacent parts of the unit; and Fig. 6 is a perspective view of the valve elements or members of the multiple valve.

The installation diagrammatically illustrated in Fig. 1 may be part of a heating plant for dwellings or other buildings and involves my improved fuel feeding and governing means with the automatic control therefor. The combustion apparatus or burner, designated, generally, by the reference character A, comprises a bowl 1 that is supported with its top wall 2 in spaced relation to the bottom wall 3 of the combustion chamber 4. The walls 2 and 3 are connected together and spaced apart by suitable means, such as shouldered rivets 5. Said walls have aligned openings surrounded by depending flanges 2^a and 3^a that are in concentric, spaced relation to each other and define a slot S for the admission of secondary air to the burner bowl, as will hereinafter more fully appear. Primary air is admitted to the bowl through perforations 6 in its peripheral wall. A relatively large lighting and cleanout opening is formed in said wall and the same is surrounded by a radially projecting neck 8 normally closed by a plug 9 shown as having a bayonet joint connection with the neck. The combustion apparatus comprising the bowl 1 and chamber 4 may be that of a furnace of appropriate type for use in heating plants or systems of the class above mentioned. For more detailed information on such apparatus, reference may be had to Letters Patent Nos. 1,944,593 and 1,979,865, dated January 23, 1934, and November 6, 1934, respectively.

Liquid fuel is supplied to the burner A from a source B (represented as a tank) through the fuel feeding and governing means designated, generally, by the reference character C. A conduit 10 leads from the source B to a float chamber 11, communicating with the interior thereof through a port 14 controlled by a valve 15. A

spring 16 tends to lift the valve from its seat, and the valve is closed by a float 18 that is carried by a lever 19, fulcrumed on a pivot pin 20 suitably supported in the valve chamber. The end of the lever remote from the float bears against the head of the valve 15. The mechanism including the valve 15 and float 18 constitutes the liquid level control that establishes the maximum fuel level in the system. The valve chamber 11 communicates, through a tubular outlet extension 25, with the casing 26 of a so-called metering valve. The valve proper, designated 27, is adapted to be manually adjusted between full open and closed positions by appropriate means including a stem 28. The valve 27, shown as having the usual thread connection at 30 with the valve casing, is provided with a graduated notch 32 by which the flow through the valve casing may be accurately controlled when the valve is in any other than full open or closed positions. The outlet of the valve casing 26 communicates, through a conduit 33, with the burner bowl 1. A by-pass duct 35 establishes communication between the interior of the float chamber 11 and the outlet connection 25, and the flow of fuel therethrough is controlled by a needle valve 36, this valve being left open at all times far enough to pass sufficient fuel to sustain operation of the burner at low or pilot fire of desired volume, and provided, of course, that the metering valve 27 is open.

Flow of fuel to the burner, when the metering valve is open, is further controlled by the multiple valve to which reference has previously been made. This multiple valve includes two valve members 38 and 39, (Figs. 1, 4, 5 and 6) shown as tubes or sleeves slidably fitted one within the other, the outer valve member 38 being similarly fitted within a valve casing 40 shown as an integral part of the float chamber. Said valve casing 40 communicates with the interior of the float chamber through an inlet port 41, and with the outlet extension 25 through an outlet port 42. When the inner valve member 39 is fully depressed its lower end shuts off communication between the valve casing and the float chamber through the inlet port 41. The outlet port 42 is controlled by the valve member 38, the lower end of which is provided with a V-notch 43 in vertical alignment with the port 42.

As explained above, fuel in sufficient amount to sustain operation of the burner at low or pilot fire flows through the by-pass duct 35. The supply of additional fuel to the burner for producing intermediate and high fires is controlled by the valve member 38, and, assuming valve member 39 to be in open position, when valve member 38 is in position to pass the additional quantity of fuel necessary to produce intermediate fire, only a limited portion of the area of the V-notch 43 extends above the bottom edge of the port 42. The descent of the valve member 38 is limited by a stop, and preferably this stop is adjustable so that the size or volume of the so-called intermediate fire may be varied. According to the present embodiment of the invention, the stop, designated 45, consists of a collar on a stud 46 that is threaded through a part on the valve chamber 11 and said stud is adapted to be locked in any adjusted position by a nut 47. The portion of the stud above the stop 45 extends freely through an aperture in a plate 48 that is suitably fastened to the upper end of the tubular valve member 38 and consists of a part of a yoke 50.

The valve member 38 has operative connection, through the yoke 50, a link 51 and a member 52 with the free end of a thermostatic element 53, consisting of a bi-metal strip; and the valve member 39 is attached to the free end of a similar thermostatic element 54, through a member 55 and a link 56. The elements or strips 53 and 54 have their inner ends adjustably connected to a standard 58 that rises from the cover 59 of the float chamber 11. Adjustment of each strip with respect to the standard is accomplished through screws 65 that pass freely through holes in the standard and in the laterally turned end portions of the elements or strips and are threaded through bars 67, and screws 68 that are threaded through the standard 58 and bear against the elements or strips in properly spaced relation to the screws 65. By relatively adjusting the screws 65 and 68 associated with each element, such element may be rocked to vary its normal angular relation to the standard 58 and consequently change the normal positions of the valve member connected therewith.

Suitably attached to the respective thermostatic elements or strips 53 and 54 are electric heaters 70 and 71 in the form of coils of resistance wire; and when said heaters are "cold" the elements or strips occupy the positions indicated in full lines in Fig. 1 thereby to retain the valve member 39 in open position and the valve member 38 in the position determined by the stop 45—that is in "intermediate fire" position, so to speak, wherein the uncovered portion of the notch 43 is of minimum area.

The fuel feeding and governing means is desirably automatically controlled by an electric system including a transformer 75 and a thermostatic switch or so-called room thermostat 76 that is subjected to the temperature of the space heated by the combustion apparatus. The two legs of a main or house circuit, of 110 volts for example, are represented by conductors 80 and 81 that are connected, respectively, to the opposite ends of the primary winding 75^a of the transformer. The conductor 80 is represented as including a switch 82, shown conventionally as a knife switch. One side of the secondary winding 75^b of the transformer has connection, through a conductor 84, with the movable contact element 85 of the room thermostat 76, such element swinging in response to changes in temperature, as is well understood by those familiar with control systems of the kind under consideration. The opposite side of the secondary winding 75^b is connected, through a conductor 86, with one end of the heaters 70 and 71 that are attached to the thermostatic elements or strips 53 and 54, respectively. The opposite end of the heater 70 is connected, through a conductor 87 with the contact point 88 of the room thermostat, while the opposite contact point 89 of said thermostat has connection, through a conductor 90, with the corresponding end of the heater 71.

From the source B, liquid fuel is conveyed by the conduit 10 to the float chamber 11, and under the influence of the liquid level control comprising the float 18 and valve 15, the fuel in the float chamber stands at the level indicated by the dot-and-dash line a of Fig. 1. With the valve 39 normally in open position, as illustrated in the drawings, fuel is permitted to flow, under restraint of the valve 38, from the float chamber 11 through ports 41 and 42, connection 25, valve casing 26 and conduit 33 to the burner A, it be-

ing assumed, of course, that the metering valve 27 is open.

With the switch 82 closed, which is the normal condition of the switch throughout the season of operation of the apparatus, current is supplied to the transformer 75; and with the needle valve 36 set to the desired open position, a limited amount of fuel will flow through the by-pass duct 35 to the burner. The fuel thus fed is augmented by that normally passing valve members 38 and 39 from the float chamber, the aggregate amount of fuel thus supplied to the burner being sufficient to maintain operation at what has been termed intermediate fire. In other words, with the system operating under normal conditions, the fire is kept at intermediate stage. Under these circumstances the apparatus produces enough heat to maintain, against the influence of a lower outside temperature, a room or space temperature within a pre-determined range for which the thermostat 76 is set, it being understood that said thermostat is of the customary form capable of adjustment to vary the value and range of the controlled temperature.

When the room or space temperature rises above the aforesaid predetermined range, the element 85 will swing to the left into engagement with the contact 88 thereby to close the circuit that includes the secondary winding of the transformer and the heater 71; and when the elevated temperature of the energized heater 71 acts upon the thermostatic element or bimetal strip 54 it will cause said element or strip to warp to the position indicated in dotted lines in Fig. 1 thereby to depress to closed position the valve member 39 shutting off the flow of fuel from the float chamber directly to the connection 25 and thence to the burner. As long as this condition prevails, the only fuel supplied to the burner is that escaping from the float chamber through the by-pass duct 35, and with the fuel supply thus reduced the burner will operate at low or pilot fire, causing the temperature to which the room thermostat is subjected to fall. When the temperature recedes sufficiently the element 85 will swing back to neutral position opening the circuit to the heater 71 and allowing the thermostatic element or strip 54 to cool and return to normal position wherein it retains the valve member 39 in open position, allowing the burner to proceed at intermediate fire.

Upon a lowering of room temperature sufficiently to cause the element 85 of the room thermostat to swing over into engagement with the contact 88, the circuit including the secondary winding of the transformer and the heater 70 will be closed, and when the elevated temperature of the energized heater 70 acts upon the thermostatic element or strip 53 it will cause the latter to assume the position shown in dotted lines in Fig. 1 thereby, through the member 52, link 51 and yoke 50, to lift the valve member 38 so as to increase the flow of fuel from the float chamber through the ports 41 and 42 to the connection 25 and thence to the burner, causing the burner to operate at high fire; and under the influence of the additional heat generated by the apparatus the temperature affecting the room thermostat 76 will rise enough to cause the element 85 to return to neutral position and open the circuit to the heater 70, after which the system will resume normal operation with the burner functioning again at intermediate fire.

In a practical application of the invention, the elements of the fuel feeding and governing means C may assume the physical form and relation illustrated in Figs. 2 to 6. As shown in Figs. 2 and 4, the float chamber 11 is provided with a relatively large hollow boss that constitutes the previously mentioned outlet connection 25; and the outer end of this boss has a leak-proof connection with the casing 26 of the metering valve, the parts being fastened together by screws 95.

The electrical connections to the heaters 70 and 71 are, in practice, made through binding posts 96 (Figs. 3 and 4), that are carried by a shelf 97 of insulating material suitably fastened to and supported by the standard 58 that rises from the cover 59 of the float chamber, the cover, with the parts mounted thereon, being shown in Fig. 3 as removed from the float chamber.

Attention is called to the fact that the tops 20 of the valve casings 26 and 40 are a substantial distance above the maximum liquid level in the system, wherefore stuffing boxes or other seals are rendered unnecessary and freedom of action of the valves is assured.

Upon reflection, it will be seen that my invention provides, in fuel feeding and governing means that functions to continue to deliver sufficient fuel to the burner to sustain operation thereof at low fire, two valves arranged in tandem, so to speak, the first of which is normally open wide enough to pass the maximum amount of fuel to be fed, and the second of which is normally open only part way so as to restrict the amount of fuel to that required for intermediate fire, means being provided for operating the first valve while the second is in normal position thereby to diminish the fuel supply to that required for low fire, plus means for further opening the second valve while the first is in normal position thereby to increase the fuel supply to that required for high fire.

Having thus described my invention, what I claim is:

1. In combination, a liquid fuel burner, a source of liquid fuel supply, and fuel feeding and governing means through which the source communicates with the burner and having provisions for continually delivering sufficient fuel from said source to the burner to sustain operation thereof at low fire, said means including, in addition to and independently of said provisions, two valves that control a single passageway and one of which is constantly open although, normally, only a minimum amount so as to permit under such conditions sufficient additional fuel to flow to the burner to sustain operation of the burner at intermediate fire, the other valve being operable between open and closed positions, means for operating the second mentioned valve to shut off the flow of the additional fuel, and means for further opening the first mentioned valve while the second is in open position thereby to increase the amount of fuel fed to the burner sufficiently to sustain operation of the burner at high fire.

2. In combination, a liquid fuel burner, a source of liquid fuel supply, and fuel feeding and governing means through which the source communicates with the burner, the same functioning to continually deliver sufficient fuel from said source to the burner to sustain operation of the burner at low fire, said means including a multiple valve comprising members that, when in normal open position, permit sufficient additional fuel to flow to the burner to sustain operation thereof at intermediate fire, and automatic con-

trol means influenced by the temperature of the space heated by the burner for operating one valve member to shut off the flow of the additional fuel when said temperature is above a predetermined value, and for further opening the second valve member while the first is in normal position to increase the quantity of additional fuel fed to the burner in sufficient amount to sustain operation of the burner at high fire when said temperature is below a predetermined value.

3. In combination, a liquid fuel burner, a source of liquid fuel supply, and fuel feeding and governing means through which the source communicates with the burner, the same functioning to continually deliver sufficient fuel from said source to the burner to sustain operation of the burner at low fire, said means including an outer tubular valve member and an inner tubular valve member operating within the former valve member, said members, when in normal relative position, permitting sufficient additional fuel to flow to the burner to sustain operation of the burner at intermediate fire, means for operating one of said valve members to shut off the flow of additional fuel while the other valve member is in normal position, and means for operating said other valve member while the first mentioned valve member is in normal position thereby to increase the quantity of additional fuel fed to the burner in sufficient amount to sustain operation of the burner at high fire.

4. In combination, a liquid fuel burner, a source of liquid fuel supply, and fuel feeding and governing means through which the source communicates with the burner, the same functioning to continually deliver sufficient fuel from said source to the burner to sustain operation of the burner at low fire, said means including an outer tubular valve member and an inner tubular valve member operating within the former valve member, said members, when in normal relative position, permitting sufficient additional fuel to flow to the burner to sustain operation of the burner at intermediate fire, means for operating one of said valve members to shut off the flow of additional fuel while the other valve member is in normal position, and means for operating said other valve member while the first mentioned valve member is in normal position thereby to increase the quantity of additional fuel fed to the burner in sufficient amount to sustain operation of the burner at high fire, said inner tubular valve member extending a substantial distance above the maximum fuel level of said feeding and governing means and being vented to the atmosphere.

5. In combination, a liquid fuel burner, a source of liquid fuel supply, and fuel feeding and governing means through which said source communicates with said burner including a delivery element functioning to continually deliver fuel from said source to said burner in sufficient quantity to sustain operation of the burner at low fire,

said means comprising a casing enclosing a valve chamber interposed between said source and said burner independent of said delivery element, said chamber having a single through passageway, a pair of valve members operable within said chamber and cooperating to control the passage of fuel through said passageway, said valve members being movable to three different relative positions in the first of which the passageway through the chamber is closed, in the second of which the passageway through the chamber is partially open, and in the third of which said passageway is entirely open, and thermostatically controlled means for moving said valve members.

6. In combination, a liquid fuel burner, a source of liquid fuel supply, and fuel feeding and governing means through which the source communicates with the burner and functioning to continually deliver sufficient fuel from said source to the burner to sustain operation thereof at low fire, said means including a single passageway and two valves in tandem for controlling the passage of fuel therethrough, the first of which valves is normally open wide enough to pass the maximum amount of fuel to be fed, and the second of which is normally open only part way so as to limit the amount of fuel fed to that required for intermediate fire, means for operating the first valve while the second valve is in normal position to diminish the amount of fuel being supplied to the burner to that required for low fire, and means for further opening the second valve while the first is in normal position thereby to increase the amount of fuel fed sufficiently to sustain operation of the burner at high fire.

7. In combination, a liquid fuel burner, a source of liquid fuel supply, and fuel feeding and governing means through which the source communicates with the burner and functioning to continually deliver sufficient fuel from said source to the burner to sustain operation thereof at low fire, said means including a single passageway and two valves in tandem for controlling the passage of fuel therethrough, the first of which valves is normally open wide enough to pass the maximum amount of fuel to be fed and the second of which is normally open only part way so as to limit the amount of fuel fed to that required for intermediate fire, and automatic control means of thermostatic character for operating said valves, the same being subjected to and so affected by the temperature of the space heated by the burner, when said temperature is above a predetermined value, as to operate the first valve while the second is in normal position thereby to reduce the quantity of fuel flowing to the burner to that required for low fire and, when said temperature is below a predetermined value, as to further open the second valve while the first is in normal position thereby to increase the quantity of fuel fed to the burner sufficiently to sustain operation of the burner at high fire.

THEODORE B. FOCKE.
